UNITED STATES PATENT OFFICE.

WILLIAM A. EVERE, OF MARTINSBURG, WEST VIRGINIA.

RAZOR-BLADE HOLDER.

Application filed January 24, 1923. Serial No. 614,672.

To all whom it may concern:

Be it known that I, WILLIAM A. EVERE, a citizen of the United States, residing at Martinsburg, in the county of Berkeley and State of West Virginia, have invented certain new and useful Improvements in Razor-Blade Holders, of which the following is a specification, reference being had to the accompanying drawings.

16 This invention relates to improvements in razor blade holders, and more particularly to a device of this character in which razor blades may be secreted and held and from which they may be extended for use in a cutting operation.

An important object of this invention is to provide a device of this character for holding standard types of safety razor blades.

20 A still further object of the invention is to provide a device of this character for simultaneously holding two different types of blades.

It is well known to those familiar with the art that blades of the Gillette type are generally made very thin and are easily bent and accordingly are only adapted for use in very light cutting whereas other types of blades having a single cutting edge are made relatively stiffer and accordingly are capable of use for heavier work. It is the purpose of this invention to provide a holder by means of which one blade of each type may be held.

35 An additional object of the invention is to provide novel and improved means for holding the blades in both concealed and extended position and to provide a structure whereby the blades may be easily extended for use.

40 These and other objects I attain by the construction and arrangement shown in the accompanying drawings wherein for the purpose of illustration is shown a preferred embodiment of my invention and wherein like reference characters designate like parts throughout.

In the drawings:-

Figure 1 is a perspective of one form of holder;

Figure 2 is a perspective of a slightly modified form thereof;

Figure 3 is a section on the line 3-3 of Figure 1;

Figure 4 is a side elevation of the form

shown in Figure 1, the blades being extended; and

Figure 5 is a section on the line 5-5 of Figure 4.

Referring now more particularly to the drawings, the numeral 10 indicates a casing longitudinally elongated and substantially rectiform in cross section, being in the form of a relatively wide, narrow oblong. This casing has formed therethrough a longitudinally extending opening 11 which opens through the ends of the casing and which is in communication with a slot 12 opening through a narrow wall of the casing at one end of the casing and extending to and slightly beyond the center thereof. The casing is provided in its side walls with openings 13 and 14 communicating with the slot 11 thereof.

At one end the slot 11 of the casing is of a width sufficient to accommodate a blade G and a cam 15, the casing being notched at this end to allow operating space for a clamping nut 16 mounted upon the end of a pivot screw 17, the head of which is mounted in the opposite wall of the casing and which extends through the blade G in an opening 18 normally employed for holding the blade in position upon the razor with which it is used and formed adjacent one end of the blade and through the cam 15. Adjacent this end of the casing the opening 11 is enlarged, as indicated at 19, to the thickness of a second blade E, the end of the enlargement forming a shoulder limiting the movement of the blade E toward that end of the casing in which the pivot bolt is mounted. From this point the opening 11 of the casing tapers towards the opposite end 20 of the casing where it is of a thickness equal to the thickness of the blade E and of a slide plate 21 having an operating end 22 which may extend through the wall of the casing either at the opening 14 or through the enlargement 12^a of the slot 12. Adjacent the end of the casing a lug 23 is formed through which extends a threaded aperture adapted for the reception of a thumb screw 24 which may be extended through the wall of the casing at this point for engagement with the plate 21 to lock the plate 21 or plate 21 and blade E against longitudinal movement in the opening 11.

By an inspection of the sectional view shown in Figure 3, and which corresponds

to a section taken on a correspondingly numbered line of the construction shown in Figure 1, it will be seen that when the slide plate 21 is withdrawn by engagement 5 of the finger with the operating portion 22 thereof to that end of the slot 14 or slot 12^a remote from the end 20 of the casing, the blade E will be comparatively free to slide and may be readily projected from 10 the end 20 of the casing by engaging the same through the opening 13 in the side wall thereof. With the blade in the desired position, the slide plate 21 may be again shifted toward the end 20 of the casing and 15 the thumb screw 24 tightened with the result that the blade will be held in the desired position. It will furthermore be obvious that with the slide plate in the position shown in solid lines in this section, 20 by engaging the blade G through the opening 14, the same may be rotated about the pivot bolt 17 through the slot 12 to place the same in the position shown in solid lines in Figure 5. The opening 14 preferably communicates with the slot 12 or 25 enlargement 12^a thereof so that full and complete access to the bolt G to swing the same may be had. Since this communication of these openings would expose the 30 edge of the blade G when in the closed position to a certain extent, the sliding plate 21 in the closed position of the knife is so arranged as to cover the opening 14 and accordingly the projecting edge of the blade 35 G to prevent accidental engagement thereof with the clothing or fingers in handling the knife. The cam plate 15 is provided with an elongated tail piece 15^a which when the cam is swung with the blade to 40 the open position, the blade G extends beyond the end of the casing and reinforces that edge of the blade G which it is not intended to use. By tightening the nut 16 the cam and blade may be secured in the 45 extended position for use or in the closed position.

From the foregoing it is believed to be obvious that a holder constructed in accordance with my invention permits the 50 housing of razor blades of different types and assures proper maintenance of the same in either closed or open position. It will furthermore be obvious that this construction as hereinbefore set forth is capable 55 of some change and modification without materially departing from the spirit of my invention and I accordingly do not limit myself to such specific structure except as hereinafter claimed.

60 I claim:—

1. In a device of the type described, a casing oblong in cross section and having an opening formed therethrough, a pivot mounted in one end of the casing adapted 65 for extension through an opening formed

in a razor blade adjacent one end thereof, a cam plate mounted within the opening upon said pivot and abutting said blade, and a clamping nut on the pivot operable from the exterior of the casing to bind the 70 clamping plate against said blade, said casing having a slot formed in the side wall thereof through which the blade is rotatable to extended or closed position.

2. In a device of the type described, a 75 casing oblong in cross section and having an opening formed therethrough, a pivot mounted in one end of the casing adapted for extension through an opening formed in a razor blade adjacent one end thereof, 80 a cam plate mounted within the opening upon said pivot and abutting said blade, and a clamping nut on the pivot operable from the exterior of the casing to bind the clamping plate against said blade, said casing having a slot formed in the side wall thereof through which the blade is rotatable to extended or closed position, the casing having an opening formed in the 85 side wall thereof and communicating with said slot whereby the blade may be engaged to shift the same about its pivot from the closed position.

3. In a device of the type described, a casing oblong in cross section and having an 90 opening formed therethrough, a pivot mounted in one end of the casing adapted for extension through an opening formed in a razor blade adjacent one end thereof, 95 a cam plate mounted within the opening upon said pivot and abutting said blade, a clamping nut on the pivot operable from the exterior of the casing to bind the clamping plate against said blade, said casing having a slot formed in the side wall thereof through which the blade is rotatable to 100 extended or closed position, the casing having an opening formed in the side wall thereof and communicating with said slot whereby the blade may be engaged to shift the same about its pivot from the closed position, and a plate 110 slideable within the opening of the casing to open or close the opening of the side wall.

4. In a device of the type described, a casing oblong in cross section and having an opening formed therethrough, a pivot mounted in one end of the casing adapted for extension through an opening formed in a razor blade adjacent one end thereof, a cam 115 plate mounted within the opening upon said pivot and abutting said blade, a clamping nut on the pivot operable from the exterior of the casing to bind the clamping plate against said blade, said casing having a slot formed in the side wall thereof through which the blade is rotatable to extended or closed position, the casing having an opening formed in the side wall thereof and communicating with said slot whereby the 120

125

130

- blade may be engaged to shift the same about its pivot from the closed position, a plate slidable within the opening of the casing to open or close the opening of the side wall, a second razor blade slidable within the opening and extensible through the opposite end of the casing from that at which the pivot bolt is located, and a clamping screw extending through the wall of the casing adjacent said end and adapted to be moved into engagement with said plate to thereby clamp the blade in extended position.
5. In a device of the type described, a casing oblong in cross section and having an opening formed therethrough, a pivot mounted in one end of the casing adapted for extension through an opening formed in a razor blade adjacent one end thereof, a cam plate mounted within the opening upon said pivot and abutting said blade, a clamping nut on the pivot operable from the exterior of the casing to bind the clamping plate against said blade, said casing having 25 a slot formed in the side wall thereof through which the blade is rotatable to extended or closed position, the casing having an opening formed in the side wall thereof and communicating with said slot whereby the blade may be engaged to shift the same 30 about its pivot from the closed position, a plate slidable within the opening of the casing to open or close the opening of the side wall, a second razor blade slidable within the opening and extensible through the opposite end of the casing from that at which the pivot bolt is located, and a clamping screw extending through the wall of the casing adjacent said end and adapted to be moved into engagement with said plate to thereby clamp the blade in extended position, the last named end of the casing having the opening thereof of a width substantially equal to the combined thicknesses of the last named blade and said plate, said opening increasing in width toward the opposite end of the casing.
- 10 40 45
- In testimony whereof I hereunto affix my signature.

WILLIAM A. EVERSON.
